(57) **CLAIM**

The ornamental design for a scoop with lip, as shown and described.

DESCRIPTION

FIG. 1 is a perspective view of a scoop with lip;

FIG. 2 is a front view of the scoop with lip;

FIG. 3 is a rear view of the scoop with lip;

FIG. 4 is a left side view of the scoop with lip;

FIG. 5 is a right side view of the scoop with lip;

FIG. 6 is a top view of the scoop with lip; and,

FIG. 7 is a rear view of the scoop with lip.

The structure depicted with dashed lines in FIGS. 1-4 and 6-7 forms no part of the claimed design.
